UNITED STATES PATENT OFFICE.

PAUL H. HORWITT, OF BROOKLYN, NEW YORK, ASSIGNOR TO INDEPENDENT PAPER MILLS, INC., OF NEW YORK, N. Y., A CORPORATION OF NEW YORK.

DEVICE FOR HOLDING STACKS OF NAPKINS AND THE LIKE.

Application filed July 6, 1923. Serial No. 649,892.

To all whom it may concern:

Be it known that I, PAUL H. HORWITT, a citizen of the United States, and resident of the borough of Brooklyn, county of Kings, city and State of New York, have invented certain new and useful Improvements in Devices for Holding Stacks of Napkins and the like, of which the following is a specification.

- 10 My invention relates to devices for holding stacks of napkins and the like and more particularly to holders for paper napkins, paper towels, toilet paper and the like, and has for its object to provide a device of this 15 character of novel and simple construction with which the napkins or their equivalent are combined in the form of a novel stack so as to be capable of individual removal with a minimum of effort and without waste. 20 Other more specific objects of the invention will appear from the description hereinafter.

In the accompanying drawings which show examples of the invention without defining its limits, Fig. 1 is a plan view of one form of the device; Fig. 2 is an elevation partly in section; Fig. 3 is a sectional elevation of another form of the device; Fig. 4 is a plan view thereof and Fig. 5 is a diagrammatic section illustrating on an enlarged scale the arrangement of napkins or their equivalent in a stack.

The invention consists essentially in a holder with which a supply of napkins or their equivalent stacked in a novel manner, is combined and a member or means located adjacent to an end of said stack and adapted to permit one corner of the terminal napkin, which has been turned back to form a flap, to project outwardly from said terminal napkin in a position to facilitate the removal of said terminal napkin from said stack. To attain this result the napkins or their equivalent have non-registering corners turned back to form flaps which are progressively released and permitted to project outwardly from their napkins or their equivalent as each napkin reaches the end of the stack and becomes the terminal napkin therein. The means or member whereby this result is accomplished is, generally speaking, in the form of a frame having corner members so located and arranged as to press against all parts of one end of the stack except the turned back corner or flap of the terminal napkin.

As shown in Figs. 1 and 2 the device comprises a base 10 from which a pedestal 11 projects upwardly and carries at its upper end a support 12 which may be in the form of a plate of a size to accommodate the napkins or their equivalent. The napkins *a* in this form are stacked and each napkin has a corner turned back to form a flap *b*, the flap of each napkin being out of registry with the flaps of adjacent napkins; that is to say, the napkins or their equivalent which constitute the stack have non-registering corners turned back as indicated to provide the flaps *b*. The device comprises further a means or member in the form of a rectangular frame 13 adapted to rest upon a stack of the napkins and having corner members 14 of triangular form as shown in Fig. 1. In the preferred arrangement flanges 15 depend from the frame 13 in a manner to guide the same in its movements and to enclose the stack of napkins *a* or their equivalent.

In practice the stack of napkins is placed upon the support 12 and the frame 13 is placed upon the upper end thereof so that the corner members 14 rest upon the upper end of the stack and extend over the four corners thereof. The stack is thus depressed while the flap *b* of the uppermost or terminal napkin *a*, being free, is caused by its inherent resiliency to project or extend away from its napkin at an angle as shown approximately in Fig. 2. The flap is thus in a position to be easily grasped by the fingers and to be utilized to remove or pull the terminal napkin from the stack. It will be understood that the flaps *b* of all but the terminal napkin are maintained in a folded or turned back condition by the adjacent napkins *a* which lie over the same and by the pressure exerted through the medium of the corner members 14 of the frame 13. As each napkin *a* or its equivalent becomes the terminal napkin of the stack its flap *b* will be released and permitted to assume the inclined position indicated in Fig. 2 thus serving in the previously indicated manner as a means for readily withdrawing said terminal napkin from the stack. It will be understood that the corner members 14 and the flaps *b* are so dimensioned that each of the latter will be free to assume the inclined position hereinbefore mentioned when its napkin becomes the terminal napkin of the stack. The dependent flanges 15 or their

equivalent prevent the removal of the napkins from the stack in anything but the intended manner and at the same time protect the napkins or their equivalent against indiscriminate handling and consequent contamination.

In the form illustrated in Figs. 1 and 2 the napkins are folded into squares while in the form shown in Figs. 3 and 4 the napkins ¹⁰ α' are folded into oblong rectangular form, that is to say, in the latter case the diagonally opposite corners of successive napkins are turned over to provide flaps β' corresponding to the flaps β previously referred to, otherwise the form of the invention shown in Figs. 3 and 4 may be the same in operation as the form shown in Figs. 1 and 2. The frame 13^a, however, instead of having corner members 14 is constructed in ²⁰ the form of a plate with corner recesses 14^c with which the flaps β' are adapted to register and with edge slots 14^b through which the terminal napkin α' is withdrawn by its flap β' when removal from the stack is ²⁵ desired. If desired, one or both forms of the device may be provided with rods 16 projecting upwardly from the supporting plate 12 and serving to position the stack of napkins or their equivalent thereupon. In such ³⁰ case as shown in Fig. 4 the frame 13^a which corresponds to the frame 13 of Figs. 1 and 2, may fit exteriorly over said rods 16 as shown in Fig. 4.

It will be understood that the construction ³⁵ and arrangement of the device may be otherwise than as disclosed in the illustrated examples and that the support 12 might move toward the frame 13 or 13^a which in such case would be stationary or the frame 13 or 13^a might be caused to exert an upward pressure ⁴⁰ on the stack which in such case would have its terminal napkin at the lower end from which successive napkins would be removed in the previously indicated manner.

In whatever form the invention may be ⁴⁵ constructed it eliminates waste and makes it easy to procure as many napkins as may be desired and displays the napkins for use in a sanitary wholesome condition.

It will be understood that I have used the ⁵⁰ term "napkins" to include anything which

may be considered the equivalent of a paper napkin such as fabric napkins, paper or fabric towels, toilet paper and the like.

Various changes in the specific form shown ⁵⁵ and described may be made within the scope of the claims without departing from the spirit of my invention.

I claim:

1. The combination of a holder, a stack ⁶⁰ of rectangular sheets combined therewith and having corners turned back to form flaps and means located adjacent to an end of said stack and arranged to permit the flap of a terminal sheet to project away ⁶⁵ therefrom whereby said flap may be grasped to remove said terminal sheet from said stack.

2. The combination of a holder, a stack ⁷⁰ of rectangular sheets combined therewith, said sheets having non-registering corners turned back to form flaps and a member adapted to exert pressure against said stack at all parts of one end thereof excepting ⁷⁵ the flap of the terminal sheet whereby said flap is free to project away from its sheet to facilitate the removal thereof from said stack.

3. The combination of a holder, a stack ⁸⁰ of paper napkins combined therewith and having corners turned back to form flaps, the flap of each napkin being out of registry with the flaps of adjacent napkins and a frame having corner-members adapted to press against said stack and to permit the ⁸⁵ flap of the terminal napkin to project outwardly therefrom to facilitate the removal of said terminal napkin from the stack.

4. The combination of a holder, a stack ⁹⁰ of paper napkins combined therewith and having corners turned back to form flaps, the flap of each napkin being out of registry with the flaps of adjacent napkins, a frame having corner-members adapted to rest upon said stack and to permit the flap of the terminal napkin to project outwardly therefrom to facilitate the removal of said terminal napkin and flanges depending from said frame and enclosing said stack.

In testimony whereof I have hereunto set ¹⁰⁰ my hand.

PAUL H. HORWITT.
